(57) **CLAIM**

We claim the ornamental design for a temperature sensing device, as shown and described.

DESCRIPTION

FIG. 1 is a perspective view of the temperature sensing device;

FIG. 2 is a front view of the design of FIG. 1;

FIG. 3 is a left view of the design of FIG. 1;

FIG. 4 is a top view of the design of FIG. 1;

FIG. 5 is a bottom view of the design of FIG. 1; and,

FIG. 6 is a right view of the design of FIG. 1.

The ornamental design which is claimed is shown in solid lines in the drawings. The broken lines in the drawings are for illustrative purposes only and form no part of the claimed design.
